(57) **CLAIM**

The ornamental design for a smart watch, as shown and described.

DESCRIPTION

FIG. 1 is a bottom, front, and right perspective view of the smart watch showing our new design.

FIG. 2 is a front view of the smart watch of FIG. 1.

FIG. 3 is a rear view of the smart watch of FIG. 1.

FIG. 4 is a left side view of the smart watch of FIG. 1.

FIG. 5 is a right side view of the smart watch of FIG. 1.

FIG. 6 is a top view of the smart watch of FIG. 1.

FIG. 7 is a bottom view of the smart watch of FIG. 1.

FIG. 8 is a bottom, front, and right perspective view of a first component of the smart watch in FIG. 1.

FIG. 9 is a front view of the first component of the smart watch of FIG. 8.

FIG. 10 is a rear view of the first component of the smart watch of FIG. 8.

FIG. 11 is a left side view of the first component of the smart watch of FIG. 8.

FIG. 12 is a right side view of the first component of the smart watch of FIG. 8.

FIG. 13 is a top view of the first component of the smart watch of FIG. 8.

FIG. 14 is a bottom view of the first component of the smart watch of FIG. 8.

FIG. 15 is a bottom, front, and right perspective view of a second component of the smart watch in FIG. 1.

FIG. 16 is a front view of the second component of the smart watch of FIG. 15.

FIG. 17 is a rear view of the second component of the smart watch of FIG. 15.

FIG. 18 is a left side view of the second component of the smart watch of FIG. 15.

FIG. 19 is a right side view of the second component of the smart watch of FIG. 15.

FIG. 20 is a top view of the second component of the smart watch of FIG. 15; and,

(Continued)

FIG. 21 is a bottom view of the second component of the smart watch of FIG. 15.

The ornamental design which is claimed is shown in solid lines in the drawings.

1 Claim, 12 Drawing Sheets
